Application October 29, 1931, Serial No. 571,736
 Renewed March 6, 1936

3 Claims. (Cl. 250—14)

My invention is for a radio receiver housed in a shallow inexpensive cabinet adapted to be hung on a wall like a picture or set in a recess in the wall. A receiver of this kind is especially useful 5 in city apartments where rooms are small and have scarcely enough floor space to hold the necessary furniture.

The problem of limited floor space in the small homes of city dwellers has occupied the attention 10 of radio manufacturers, and so we have recently had the so-called shelf or table models and the tall columnar models in the shape of grandfather clocks. But even the latter require floor space and are furthermore expensive on account of the 15 necessary cabinet work and the enclosed clock. As for the midget sets, they require another piece of furniture to support them, such as a desk, a shelf, or mantel, and these may not always be on hand or may be filled with other things. A further 20 objection to the midget sets is the close crowding of the parts into very small space, so that disturbing electric interactions are liable to occur, not to mention the difficulty of getting at the parts when necessary.

25 I have solved the problem in a different way: by constructing a radio receiver that can be hung on a wall in any convenient position. Every room, no matter how small or cluttered with furniture, has plenty of free wall space, so there is no difficulty in placing my new type of wall receiver in such a room. Another practical advantage of 30 my receiver lies in the low cost of the shallow cabinet in which the parts are mounted. The sides of the cabinet are so narrow as to require no 35 fancy finish or ornamentation, and only the front panel need be of attractive appearance. Furthermore, the constituent parts of the receiver are supported on shelves without being crowded and are thus fully exposed for easy access when the 40 door of the cabinet is opened.

The novel features and utility of my invention will be fully understood from a description of the accompanying drawings, in which—

45 Fig. 1 is a small perspective view of my new wall receiver;

Fig. 2 is a front view of the open cabinet on a larger scale;

Fig. 3 is a vertical section on the broken line 50 3—3 of Fig. 2;

Fig. 4 is a sectional plan view on line 4—4 of Fig. 2;

Fig. 5 shows an enlarged vertical section on line 55 5—5 of Fig. 2, the central portion of the cabinet being broken away for lack of space;

Fig. 6 is a fragmentary sectional view of the volume-control mechanism;

Fig. 7 represents an enlarged view of a portion of the cone speaker construction;

Fig. 8 is a fragmentary view showing the 5 mounting of a radio tube on a shelf in the cabinet;

Fig. 9 is a vertical section of the left end of the 10 cabinet to show one form of latch device for the front panel;

Fig. 10 is a fragmentary view, partly in section, 15 of a modification in which the rotary tuning knob is axially adjustable to volume-controlling position;

Fig. 11 is a section on line 11—11 of Fig. 10;

Fig. 12 is a section on line 12—12 of Fig. 11;

Fig. 13 shows an enlarged section through the 20 combined tuning and volume-controlling knob of Fig. 10;

Fig. 14 is a section on line 14—14 of Fig. 11;

Fig. 15 shows how the vacuum tubes may be 25 supported in a horizontal position; and

Fig. 16 illustrates a modified driving connection 30 between the tuning shaft and a knob projecting from the bottom of the cabinet.

The outer cabinet C is a shallow casing, usually 35 of wood or other insulating material, comprising a back wall 10, narrow side pieces 12 and 13, a bottom or base plate 14, a top section 15, and a front panel or door 16, which is hinged at 17 or otherwise movably connected to the cabinet.

The depth of the cabinet need not be more than 40 five inches and may even be less; the width as a rule will be about eighteen or twenty inches, and the total height about thirty inches. I give these figures merely by way of example and not in a 45 restricted sense. The panel 16 may be covered with tapestry or a painted canvas, or it may carry a mirror, particularly if the cabinet is to be hung over a mantel. The top section 15 is here shown as an ornamental dome-like extension which forms a chamber 18 for housing a 50 cone loudspeaker indicated as a whole by L. The structural details of the loudspeaker will be described later on. A partition 19 preferably separates the sound chamber 18 from the rectangular main compartment 20 in which the other constituent parts of the receiver are mounted. In the present instance, the compartment 20 contains a pair of shelves 21 and 22 secured to the back wall 10 by brackets 23 or in any other practical way. These shelves may be 55 strips of wood, bakelite, or other insulating material.

The upper shelf 21 supports all the vacuum 55

tubes 24 required by the particular type of receiver circuits employed, these tubes being preferably arranged in a single row for easy access. It may be assumed that the large left-hand tube 5 24' is a rectifier tube, while the others are the usual detector and amplifier tubes, as will be understood without further explanation. The contact pins 25 of the vacuum tubes pass through openings in shelf 21 into pressure engagement 10 with spring contacts 26 secured to the underside of the shelf (see Fig. 8). The tight frictional fit of contact pins 25 in the shelf holds the tubes firmly in place. In Fig. 2 the tubes 24-24' are supported in vertical position, and in Fig. 15 they 15 are mounted horizontally on a vertical base 27 attached to the back wall 10. A horizontal shelf 28 projecting from base 27 or the back wall 10 holds the tubes against accidental displacement. If the receiver has so many tubes that they can 20 not all be mounted on the shelf in a single row, some of the tubes may be arranged in a second row, as indicated at 24a in Fig. 3.

The lower shelf 22 is this instance supports 25 all operative parts of the receiver other than the vacuum tubes and tuning condensers. In Fig. 2 I have indicated by way of example a power pack 29 and three transformers 30 covered by a common metal shield 31. There will, of course, be other electrical devices, depending upon the kind 30 or type of circuits used—such as by-pass condensers, resistances, regenerative coils and other requisite parts with which every radio engineer is familiar. A suitable volume-controlling unit indicated as a whole by V may also be mounted 35 on shelf 22 for operation by a rotary hand knob 32 projecting from the front panel 16. The structural details and operating connections of this volume-control unit will be described in due course. It is evident that the tubes 24-24'-24a 40 can be mounted on the lower shelf 22, and the electrical parts 29, 30, etc., transferred to shelf 21.

The space between the lower shelf 22 and the bottom plate 14 of the cabinet contains the necessary tuning condensers K of the usual type 45 and number. By way of example I have shown four sets of condenser plates in two gangs mounted on a pair of vertical rotary shafts 33, which are supported in a U-shaped bracket 34 attached to the back wall 10 by screws 35 or otherwise. 50 Although I have shown only two condenser gangs and two supporting shafts 33, it is obvious that as many more condensers and shafts may be added as are necessary for the particular type of receiver housed within the cabinet. The supporting bracket 34, which may conveniently be a single casting of aluminum, has a pair of vertically aligned bearings 36 and 37 (see Figs. 5 and 10) for supporting a rotary shaft 38. This shaft carries a pair of spaced bevel gears 39-40 and a 55 pair of pulleys 41-42, which may be a single pulley with a double groove. The condenser shafts 33 are provided with pulleys 43 and 44 (see Fig. 2) which are connected to the driving pulleys 41 and 42 respectively by belts 45 and 60 46. Instead of using belts or pulleys for connecting the driving shaft 38 with the tuning shafts 33, I may use any other practical form of transmission means.

The front door or panel 16 of the radio 65 cabinet carries a rotary knob 47 which operates a bevel pinion 48 arranged in mesh with the bevel gear 40 on the vertical driving shaft 38. The gear reduction between parts 48 and 40 may be about 1:4. A simple way to connect the parts 70 47 and 48 is to secure them to the opposite ends

of a rotary pin or stud 49 journalled in a suitable bearing member 50, which is mounted on the inner wall of the hinged door 16, as clearly shown in Fig. 5. The meshing bevel gears 48 and 40 are readily separable and engageable to permit closing and opening of door 16. The gear teeth may be slightly rounded at the outer edges, so that the pinion 48 slides easily into mesh with gear 40 when the door 16 is closed. If we assume that the tuning shafts 33 change the capacity of the 10 condensers from minimum to maximum in half a revolution, the operating knob 47 will require several turns to cover the full tuning range.

Referring to Fig. 5, the bracket 34 has a top bearing 51 adapted to support a rotary pin or 15 stud 52, which carries a bevel gear 53 arranged in permanent mesh with the bevel gear 39 on shaft 38. On the outer end of pin 52 is mounted a dial plate 54, which has suitable notations 20 thereon to indicate the various broadcasting stations in the usual way. The station indications on the dial 54 are visible through an opening 55 in the front panel 16. The gears 39 and 53 are in a 1:1 ratio, because it is assumed that the frequency or wave length indications on dial 54 25 extend over an arc of 180 degrees. It should be noted that the rotary dial 54 is in permanent relation to the condenser shafts 33, and this relation is not disturbed by the separation of gears 48 and 40 when the door 16 is opened. Nor does 30 it matter if somebody should idly spin the knob 47 when the door is open, because it is only when the pinion 48 is in mesh with the bevel gear 40 that the tuning shafts 33 and dial 54 are operated in synchronism.

A small electric light bulb 56 may be mounted 35 on shelf 22 behind the dial 54 to illuminate the notations appearing thereon. If the dial 54 is opaque, the light from lamp 56 is thrown by a small reflector 57 into the narrow space 57' for 40 illuminating the front of the dial. The reflector 57 is preferably mounted on the back of panel 16, so that the lamp 56 is fully accessible when the panel is swung open. If desired, however, the reflector 57 may be attached to shelf 22 in any 45 convenient way. Instead of a movable dial plate 54 and a fixed pointer 58, I may use the equivalent reverse arrangement consisting of a movable pointer and a fixed dial. It should be noted that the tuning condensers and station indicator, together with their driving connections, are all 50 carried by the bracket 34 and thus constitute a unitary structure which can be assembled on the work bench and placed in the cabinet as a single piece of apparatus.

The loudspeaker L comprises a cone diaphragm 59 which need be not more than five or six inches in diameter and may be less than four inches deep. The concave side of diaphragm 59 faces a round opening 60 in the cabinet for emission of 60 sound waves generated by the diaphragm. The opening 60 is covered by an ornamental grille or other perforated member 61, which is removably held in place by any practical means. The mouth of diaphragm 59 terminates in a flat annular 65 flange 62 adapted to be engaged by a clamping ring 63, which is secured by screws 64 or otherwise to the surrounding framework 65 of the cabinet. The flange 62 of the diaphragm may be cemented or otherwise secured to the clamping ring 63. The latter carries a cross-arm 66 to which the field magnet of the electromagnetic driving unit is secured. The parts 63 and 66 may be a single casting of duralumin which is light, 70 strong and non-magnetic. The cross-arm 66 has 75

a circular enlargement 67 at the center for supporting the circular base 68 of the field magnet indicated as a whole by M. Screws or other fastening members 69 hold the magnet M rigidly to the cross-arm 66.

A magnetic shell 70 is attached to the base plate 68 by screws 71 or otherwise, so that the two parts are held in intimate magnetic contact as if they were a single member. The base of shell 70 has approximately the same diameter as the disk 68, but the polar end 70' of the shell is contracted to form a narrow annular airgap 72 with a central cylindrical pole piece 73 projecting rearwardly from the base 68 of the magnet. The parts 68 and 73 may be a single casting, or secured together as separate pieces. If 73 is the north pole of the magnet, the surrounding annular pole piece 70' will be the south pole, and vice versa. The magnet M may be either a permanent magnet or an electromagnet. In the latter case the magnet is of material having high magnetic permeability, and a field coil 74 is mounted on the central pole piece 73. The coil is, of course, positioned before the shell 70 is attached to the base member 68.

The cone diaphragm 59, which may be made of stiff paper, celluloid, impregnated cloth, or even thin sheet metal, carries a light non-magnetic shell 75 for supporting a speech coil 76. The rear end 77 of diaphragm 59 may be closed and consist of a flat disk to which the flat flange 78 of the coil form 75 is secured by cementing or otherwise. To prevent lateral displacement of the speech coil 76 in the annular airgap 72, I place a thin stretched band 79 of rubber or like material over the end of pole piece 73 for engaging the coil form 75 and thereby holding it in concentric relation to the pole piece during the axial vibrations of the coil. This construction is clearly shown in Fig. 7, which is grossly exaggerated for clearness. By mounting the magnet M within the conical space formed by the front face of the diaphragm, it is possible to accommodate the entire loudspeaker mechanism in the shallow chamber 18, which is not much deeper than the axial length of the cone diaphragm itself. This is apparent from Figs. 3 and 5.

Attention is called to the fact that the parts of the loudspeaker may be assembled into a unitary structure before the latter is attached to the cabinet by the screws 64. To remove the loudspeaker from the cabinet (as for inspection or repair), it is only necessary to take off the cover 61 and loosen the screws 64. Should it be found in any particular instance that the chamber 18 produces undesirable resonance due to sound waves generated back of the diaphragm, it is only necessary to line the chamber with felt, soft rubber, or other sound-absorbing material 80. This acoustic insulation of the loudspeaker from the rest of the cabinet also tends to eliminate vibration of the vacuum tubes 24 during the operation of the loudspeaker. If necessary or desirable, the acoustic chamber 18 may have openings 81 for the escape of sound from the back side of the diaphragm.

Referring to Fig. 6, the volume-controlling device V comprises an insulating base plate 82 fixed in vertical position on shelf 22, and this plate has an integral circular projection 83 which supports a resistance coil 84 wound on an insulating ring 85. A stud or pin 86 journalled in the supporting plate 82 carries at its front end a toothed clutch member 87 and a contact arm 88 arranged

5 arm 88 may conveniently be attached to an insulating collar 89 on shaft 86. The knob 32 is attached to the outer end of a rotary pin 90 mounted on the front door 16 and carrying at its inner end a toothed clutch member 91, which is arranged to mesh with the adjacent clutch member 87 when the door is fully closed. Fig. 6 shows the door 16 slightly opened, so that the clutch members 87 and 91 are disconnected. During the final closing movement of the door, the pointed or bevelled teeth of clutch members 87 and 91 automatically interlock, whereby the knob 32 is operatively connected to the rotary contact arm 88. It is assumed that the resistance 84 is so connected in circuit that, when the knob 32 is turned one way (usually clockwise), the volume is increased, while reverse rotation of the knob cuts the volume down. The clutch members 87 and 91 are so arranged as to mesh simultaneously with the meshing of gears 40 and 48 when the door 16 is fully closed.

It is probably most convenient to have the tuning knob 47 on the front door 16 of the cabinet, as above described. This arrangement of the tuning knob also permits the cabinet to be set in a recess in the wall, so that the front of the cabinet is substantially flush with the outer face of the wall. When the cabinet is hung on the wall like a picture, the tuning knob may project from the bottom of the cabinet, as shown in Fig. 16, where the knob 47' is attached to the lower end of a vertical shaft 92 journalled in a bearing 93. The latter may conveniently be made an integral part of the U-shaped supporting bracket 34 previously described. The upper end of the rotary shaft 92 carries a small gear wheel or pinion 94, which is permanently in mesh with a larger gear wheel 95 on the driving shaft 38. In this instance there is no need of separating the meshing gears 94 and 95, because the opening of door 16 does not disturb them. The mounting of the tuning knob 47' below the cabinet makes it practically invisible and leaves the front door 16 an unbroken surface, except for the small knob 32 and the dial opening 55. Even the knob 32 can be removed from the front panel 16 by placing the volume-controlling device V at the bottom of the cabinet so that the knob would project beneath the cabinet like the tuning knob 47' in Fig. 16.

Instead of using two separate knobs 47 (or 47') and 32, one for tuning and the other for controlling the loudspeaker volume, I provide a novel construction in which a single knob performs the triple function of tuning, controlling the volume, and turning the electric power on and off. Referring to Figs. 10-13, the front door 16 carries on the outside a bearing member 96 for supporting a shaft 97, which is capable of rotary and axial movements. The inner end of shaft 97 carries a gear wheel 98 in addition to the bevel pinion 48 which meshes with the driving gear 40 on shaft 38, as previously explained. A knob 99 is connected to the outer end of shaft 97 for rotating the latter and also pulling it out or pushing it in. When the knob 99 is fully pushed in, as shown in full lines in Fig. 10, the bevel pinion 48 is in mesh with the bevel gear 40 on shaft 38. When the knob is pulled out to the dotted position 99' in Fig. 10, the pinion 48 disengages the gear wheel 40 and the gear wheel 98 on shaft 97 is shifted to position 98' for a purpose that will presently become clear. Any suitable means may be employed to hold the shaft 97 in either of its two axial positions. In Fig. 13 the shaft 97 has a

pair of spaced annular grooves 100 and 101 adapted to receive a ball 102 which is pressed into the grooves by an expanding coil spring 103 housed in the bearing member 96. An adjustable screw 104 permits regulating the tension of spring 103, so that the ball 102 presents just the right amount of friction to lock the shaft 97 releasably in either of its two axial positions. The grooves 100 and 101 are so placed that, when the knob 99 is pushed in, the ball 102 projects into groove 100, as shown in Fig. 13. When the knob 99 is pulled out, the second groove 101 comes into alignment with the retaining ball 102.

Referring to Figs. 11 and 12, it will be seen that the front door 16 supports a rotary gears ring 105 which surrounds a circular resistance coil 106 wound on an insulating core 107. An arc-shaped strip or plate 108 is attached to the inner face of door 16 by screws 109, and this plate has a pair of integral hooks or fingers 110 which extend along the inner face of the annular core 107 and then project laterally over the same. Small screws or pins 112 connect the core 107 to the fingers 110, whereby the rheostat coil 106 is firmly held in place against the inner wall of door 16. The outer ends of fingers 110 extend over the gear ring 105, whereby the latter is retained against axial displacement. The gear ring 105 and core 107 are preferably made of insulating material like fiber or bakelite. A pin or stud 113, mounted in door 16 centrally of gear ring 105 and resistance coil 106, carries a rotary contact arm 114 which is preferably a spring finger attached to an insulating washer or bearing sleeve 115. The inner end of pin 113 carries a metal nut or collar 116, and a metallic washer 117 is interposed between the end nut 116 and the hub of arm 114. The outer end of pin 113 is formed with (or has attached thereto) a head 117 which fits in a recess 118 of the supporting door 16. A spring washer 119 located in recess 118 tends to push the pin head 117 outward, whereby the rotary arm 114 is maintained in good electrical contact with the pin 113.

A conductor 120 is connected at one end to the metal pin 113 in recess 118, and the other end of this conductor is attached to a binding post 121 secured to the inside of door 16. One end of the rheostat coil 106 is connected to a conductor 122, which leads to a binding post 123. The conductors 120 and 122 are housed in grooves 124 cut in the inner face of the door, so that the conductors will not interfere with the mounting of coil 106 and the movements of gear ring 105. The free end of the spring contact arm 114 rests in a radial slot 125 in gear ring 105, whereby the rotation of the latter in either direction carries the contact arm along. The spring arm 114 is so shaped that it remains in firm pressure engagement with the resistance element 106 during the rotary movements of the actuating gear 105. A radial extension 126 on gear ring 105 engages a pair of fixed stops 127 and 128. The angular distance between these stops is such as to confine the rotation of gear ring 105 to the maximum and minimum of loudspeaker volume. It may be assumed that the volume is loudest when the extension 106 engages the stop 128, so that the volume increases when the knob 99 is turned clockwise, as viewed from the front of the cabinet. The circuit wires attached to binding posts 121 and 123 are sufficiently loose to permit opening of the door. Another way to connect the binding posts 121 and 123 in circuit is to mount a pair of fixed terminals in the cabinet in such position that

they abut against the binding posts when the door 16 is fully closed. This separable engagement of the binding posts with the fixed terminals permits opening of the door without the need of loose wires.

It is clear from Fig. 10 that, as long as the knob 99 remains pushed in, the bevel gear 48 is in mesh with gear 40 to operate the tuning shaft, but the gear 98 on shaft 97 is out of mesh with the gear ring 105, so that the rheostat arm 114 is not actuated during the tuning operation. After the desired station has been tuned in by rotation of knob 99, the operator pulls out the knob, thereby disconnecting the pinion 48 from the tuning shaft 38 and coupling the gear 98 to the gear ring 105. If now the pulled-out knob 99 is rotated, the contact arm 114 moves over the resistance element 106 and changes the volume to higher or lower degree, depending upon the direction in which the knob is turned. When the knob 99 while in pulled-out position is turned counterclockwise until the extension 126 strikes the fixed stop 127, a switch arm 129 is moved away from its associated contact 130 and the electric power for the receiver is cut off. The switch arm 129 is shown in the form of a spring finger having a hump 129' arranged in the path of the extension 126 on gear ring 105. The normal tension of spring finger 129 holds it in pressure engagement with the stationary contact 130, so that the spring finger automatically moves to closing position when the extension 126 moves away from stop 127. The end of extension 126 is preferably bevelled or pointed, so that the switch arm 129 is not opened until just before the extension strikes the stop 127. The operator therefore knows that, when he turns the knob 99 counterclockwise as far as it will go, the power switch is open and remains in that condition until the knob is turned clockwise. The inward pressure of the opened spring arm 129 against the radial lug 126 tends to hold the gear ring 105 and all connected parts against accidental movement.

A pair of conducting strips or stiff wires 131 and 132 are connected to switch members 129 and 130, respectively, and extend downward along the inner face of door 16, as shown in Figs. 11 and 14. The lower ends of conductors 131 and 132 are bent laterally to form horizontal projections 133 adapted to engage insulated contacts 134 and 135 mounted on the bottom plate 14 of the radio cabinet. The lateral extensions 133 of conductors 131—132 are separable from the stationary contacts 134 and 135 to permit opening of the front door 16. When the door is closed, the lateral extensions 133 automatically slide into engagement with contacts 134 and 135, which may be in the form of spring fingers to assure a firm pressure engagement with the extensions 133. It is assumed that the main current leads of a storage battery or a house-lighting system are connected to the terminals 134 and 135. Another practical advantage of disconnecting the movable switch members 129 and 130 from the stationary terminals 134 and 135 lies in the fact that the opening of door 16 automatically cuts off the power, even if the switch arm 129 should be closed. A person thus knows that, when he opens the door 16 to inspect the inside mechanism, all circuits are open and there is no danger of getting an electric shock. If the receiver is to be tested while the door 16 is open, it is only necessary to connect the terminals 134 and 135 temporarily by a piece of wire, or a

movable contact arm which may be mounted on one of the terminals.

The door 16 is preferably latched in closed position to assure the meshing of gear members 48-48 and clutch members 87-91. A practical form of concealed latch device is shown in Figs. 2, 4 and 9. The door 16 carries near its left end a pair of fingers 136 arranged to be engaged by latches 137 which are pivoted at 138 to the end 10 panel 12. A vertically slidable bar 139 is pivotally connected to both latches 137 and carries at its lower end a push-button 140, which projects through an opening in the bottom of the cabinet. A contracting coil spring 141 is connected at one 15 end to rod 139 and at the other end to a fixed pin 142, whereby the latches 137 are normally held in locking engagement with the fingers 136, as will be clear from Fig. 9. When a person pushes the button 140 up, the rod 139 lifts the latches 137 to releasing position, and the door 16 20 is free to be opened. A fixed stop 143 arranged near the upper latch 137 holds both latches in substantially horizontal position when the door is opened, so that the subsequent closing of the 25 door automatically causes the bevelled ends of latches 137 to ride over the fingers 136 into locking engagement therewith.

It is desirable to provide a continuous circulation of air through the chamber 20 to carry off 30 the heat necessarily developed by the operation of the transformers and the vacuum tubes. For this purpose the bottom 14 of the cabinet has air holes 144 and at the top of the chamber are air holes 145 cut in the end panels 12 and 13. If 35 necessary, the shelves 21 and 22 may also have air holes, but as a rule that will not be necessary, because the front ends of the shelves are sufficiently spaced from the closed door 16 to permit free circulation of cooling air through the 40 entire chamber.

Although I have shown and described certain specific constructions, I want it understood that my invention is not limited to any details set forth, unless expressly included in the claims. 45 Changes and modifications will probably occur to those skilled in the art in manufacturing my invention for commercial use, without departing from the scope of the appended claims. Further, it is not necessary that all the various novel features of my invention shall be embodied in a 50 single device, for it is possible to use some fea-

tures without others. When I speak of a wall in the claims I do not necessarily mean the wall of a room, but I include broadly any wall-like or upright support to which the cabinet may be hung or otherwise attached.

5

I claim as my invention:

1. A radio receiver cabinet having a front panel movable to open position, a hand-operable rotary spindle carried by said front panel and mounted for axial movement to either of two positions, a 10 rotary tuning shaft in said cabinet, a volume-control device in said cabinet, means for establishing a separable driving connection between said spindle and said tuning shaft when the spindle is in one of its axial positions, whereby 15 said panel is free to be moved to open position, and other means for establishing a separable driving connection between said spindle and said volume-control device, only one of said driving connections being operative at one time. 20

2. A radio receiver cabinet having a rotary tuning shaft, a rotary volume-controlling member, a hand-operated shaft having rotary and axial movements, means for preventing lateral movement of said shaft, means for connecting 25 said hand-operated shaft in one of its axial positions to said tuning shaft, means for connecting said hand-operated shaft in its other axial position to said volume-controlling member, a normally closed switch having a movable contact, 30 and a rotary part operated by rotation of said shaft in volume-controlling position to move said contact to circuit-breaking position.

3. A radio receiver cabinet having a movable panel, a volume-control device mounted on said 35 panel, a rotary knob also mounted on said panel for operating said device, a power switch mounted on said panel, rotary means operated by the rotation of said knob for opening said switch and holding it open as long as said knob remains 40 in a certain radial position, a pair of terminals mounted on said panel and electrically connected to said switch, a second pair of terminals mounted in the cabinet independently of said panel, and means whereby the terminals on the 45 panel automatically move into circuit-closing engagement with the terminals in the cabinet, said engagement being separable to permit opening of the panel.

ADOLPH A. THOMAS. 50
